UNITED STATES PATENT OFFICE.

HERBERT E. KEELER, OF NEW YORK, N. Y., ASSIGNOR TO CURTAIN SUPPLY COMPANY,
OF CHICAGO, ILLINOIS, A CORPORATION OF NEW JERSEY.

CURTAIN-FIXTURE.

No. 923,794.

Specification of Letters Patent.

Patented June 1, 1909.

Application filed December 5, 1903. Serial No. 183,862.

To all whom it may concern:

Be it known that I, HERBERT E. KEELER, a citizen of the United States, and resident of New York city, in the county and State of New York, have invented certain new and useful Improvements in Curtain-Fixtures, of which the following is a specification, taken in connection with the accompanying drawings, which form a part of the same.

10 This invention relates to curtain fixtures such as are especially adapted for use in railway cars to allow the ready adjustment of the car curtains and to hold them securely in adjusted position.

15 In the accompanying drawings in which the same reference numeral refers to similar parts in the several figures, Figure 1 is an elevation partly in section showing an embodiment of this invention applied to a curtain. Fig. 2 is an enlarged detail sectional view showing one form of shoe. Fig. 3 is a transverse section through the same. Figs. 4, 5, 6, 7, 8 and 9 are sectional views similar to Fig. 2 showing other forms of shoes.

20 In the embodiment of this invention shown in the drawings, the curtain 34 is indicated as being attached at its upper end to the constantly acting spring roller 35. Suitable guideways of any desired form are provided on either side of the curtain and these guideways may take the grooved form indicated. Shoes are carried by the curtain and coöperate with these guideways, 36, and for this purpose the curtain tube 40 may be secured 25 near the bottom of the curtain in a suitable pocket or otherwise. The shoes are indicated as formed with suitable plungers 30 which fit within the ends of the tube so as to be guided in their movement and each plunger is preferably held in the tube by a suitable screw or pin 31 engaging the plunger and having its head operating in a suitable slot in the tube. Each shoe is preferably 30 pressed into coöperation with the guideway

40 by a suitable spring 32 which as indicated engages a stop 33 in the tube and operates against the end of the plunger. The shoes are preferably provided with separated guiding members to engage the guideways and 45 these guiding members preferably comprise suitable rotating guiding members which may be in the form of cylindrical rolls whose peripheries engage the guideways. One or more of these rotating guiding members in 50 each shoe may be formed with a suitable locking clutch operating between the guiding

member and the pin on which it is mounted so as to lock the guiding member against rotation in one direction. Any desired form of intermittently locking clutch may be employed for this purpose, the rotating member being locked so that under the spring pressure used its rotation in one direction by engagement with the guideway is practically prevented. If only one intermittently locking clutch is employed in each shoe, 60 this locking guiding member is preferably mounted below the other point of contact of the shoe with the guideway and in this case the intermittently locking clutch between 65 the roll and the pin is preferably arranged to lock this roll against rotation by contact with the guideway when the shoe moves upward, but to allow the guiding member to rotate when the shoe moves downward, so that 70 the curtain may be readily lowered but is prevented from being raised by the spring roller. If another intermittently locking 75 guiding member is employed in the shoe above the other the intermittently locking clutch may be arranged to lock this second 80 guiding member against rotation by the guideway when the shoe moves downward, but to allow it to be rotated by the guideway upon the upward movement of the shoe. 85

The shoe may be provided with the roll 2 mounted upon the pin 7 below the center of the shoe. This pin is preferably rigidly secured in the shoe and may be riveted to the sides of the same, if desired, as indicated in 90 Fig. 3. A suitable annular groove 5 is formed in the pin and a similar coacting groove is formed in the roll as indicated in Figs. 2 and 3 and the clutch spring 4 preferably having the curved contour indicated is 95 secured at its inner end to the pin and lies when in operative position in the coacting grooves described. The end of this light spring engages the roll as soon as the roll begins to rotate in the direction indicated by 100 the arrow in Fig. 2 and locks the roll against rotation in this direction. It is, of course, understood that these parts may be readily assembled by forcing the clutch spring into the recess 5 in the pin and thereupon inserting the pin and spring into the roll after 105 which the pin can be readily secured to the shoe, as indicated. The treads of the rotating guiding members used in this fixture may be formed of suitable material to properly co- 110 operate with the guideway and should be formed of such material as to give the proper

gripping action under the spring pressure used and if desired may be suitably roughened or corrugated for this purpose. If desired, a similar intermittently locking clutched roll 2 may be mounted at the upper end of the shoe 1 as is indicated in Fig. 2, the clutch spring 4 being so mounted in the pin 7 as to engage the groove in the roll and lock this roll 2 against rotation in the direction indicated by the arrow; so that this upper clutched roll is locked against rotation by the guideway when the shoe is moved downward, but rotates under the influence of the guideway when the shoe moves upward. If desired, however, a guiding member of any desired form may be used in connection with an intermittently locking clutched rotating guiding member in the shoe and this coöperating guiding member may, if desired, be a rotating guiding member, such as indicated in Fig. 4, in which the guide roll 6 may be mounted to rotate about a pin 3 in the shoe. The lower roll 2 is constructed and mounted as has been described in connection with Fig. 2 except that its tread is indicated as roughened or corrugated. This may, of course, be done in any case where necessary to give a greater holding action between the roll tread and the guideway. It is, of course, understood, however, that this coöperating guiding member may be non-rotary, if desired, and this may be accomplished in some cases by rigidly securing the guiding member 6 to the pin 3 by using a drive fit, for instance, or by tightly riveting the parts together so as to prevent its rotation.

Any other desired form of intermittently acting clutch may be used between the locking guiding member and its pin. Fig. 5 indicates the roll 11 mounted upon the pin 8 fixed in the shoe, this roll being provided with a suitable aperture 37 in which the pivoted clutch 9 is mounted so that its free end engages the pin 8. A suitable light spring 10 is preferably employed to hold the pivoted clutch in operative engagement with the pin, the proportion of these parts being such that the clutch locks the roll against rotation in the direction indicated by the arrow by the engagement of the guideway with the roll, that is, when the shoe is moved upward. A suitable coöperating guiding member may be mounted in the shoe preferably separated from the clutched guiding member described and this guiding member may be the roll 6 mounted to rotate about the pin 3. A suitable clutch block may be mounted in the rotary guiding member, if desired.

Fig. 6 shows the rotating guiding member 12 as mounted upon the pin 13 which is provided with the notches 39. The clutch block 14 is formed to engage these notches and is mounted within a suitable aperture in the guiding member, the outer end of the aperture being closed by the plug 16 which con-

fines the light spring 15 operating to hold the clutch block in engagement with the pin. This arrangement, as is indicated, locks the rotating guiding member against rotation when the shoe is moved upward.

A suitable spring clutch may be used instead of the clutch block indicated, Fig. 7 showing the clutched roll 17 mounted upon the pin 18 which is formed with the notches 38 and the spring clutch 20 is adapted to engage these notches, the spring being mounted in an aperture 19 in the roll.

A suitable rotary clutch member may be used, if desired, and Fig. 8 indicates the ball 23 mounted in a suitable hole in the guide roll 21 which rotates about the pin 22 fixed in the shoe 1. The plug 25 closes the outer end of the hole in which the ball is mounted and a suitable light spring 24 normally presses the ball into engagement with the pin so that the roll is locked against rotation in the direction indicated by the arrow, the angle of the hole being such as to give the proper locking action.

A number of rotary clutch members may be employed in the rotating guiding member, if desired, and Fig. 9 indicates a number of apertures 29 formed in the rotating guiding member 26 in which suitable balls or rolls 28 may be mounted to coöperate with the pin 27 upon which the guiding member 26 rotates. The apertures are formed of varying depth as indicated, so that the balls or rolls are wedged against the pin when the rotating guiding member tends to rotate in the direction indicated by the arrow and thus lock this guiding member against rotation when the shoe moves upward. The clutched guiding member may, however, be rotated in the other direction by engagement with the guideway.

It is, of course, understood that many changes may be made by those familiar with this art in the form, proportion and number of parts of this device. Furthermore, parts of the same may be employed without departing from the spirit of this invention or losing the advantages of the same. I do not, therefore, desire to be limited to the details of the disclosure which has been made in this case, but

What I claim as new and what I desire to secure by Letters Patent is set forth in the appended claims.

1. In curtain fixtures, a shoe comprising a pin formed with depressions therein, a rotating guiding member mounted on said pin and formed with an aperture, a sliding clutch in said aperture, and a spring engaging said clutch and forcing it into coöperation with said depressions to automatically restrain the rotation of said guiding member.

2. In curtain fixtures, a shoe comprising a pin formed with an annularly arranged series of depressions, a rotating guiding member mounted on said pin, and a spring actuated

clutch in said member to automatically engage said depressions and lock said member against rotation in one direction.

3. In curtain fixtures, a shoe comprising a pin formed with depressions, a rotating guiding member mounted on said pin, a clutch slidingly mounted in an aperture in said member, and a spring to normally force said clutch into coöperation with said depressions to positively lock said guiding member against rotation in one direction.

4. In curtain fixtures, a shoe comprising a pin formed with depressions, a rotating guiding member mounted on said pin and a spring-pressed clutch in said member to engage said depressions and positively lock said member against rotation in one direction.

5. In curtain fixtures, a shoe comprising a pin, a rotating guiding member mounted on said pin and a resiliently yieldable clutch in said member to engage said pin and automatically lock said member against rotation.

6. In curtain fixtures, a shoe comprising a pin, a rotating guiding member mounted on said pin and a resiliently yieldable automatic clutch between said pin and said rotating guiding member to lock said member against rotation.

7. In curtain fixtures a shoe comprising a pin, a rotating guiding member mounted on said pin, a movable clutch mounted within said guiding member, and means to yieldingly force said clutch against said pin to restrain the rotation of said guiding member.

35 8. In curtain fixtures, shoes carried by a curtain, pins in said shoes, rotating guiding members in said shoes mounted upon said pins, and means engaging said pins and rotating guiding members for resisting the relative movement between them.

9. In curtain fixtures, a shoe comprising a pin, a rotating guiding member mounted on said pin, and means engaging said pin and said rotating guiding member to restrain the rotation of said guiding member.

10. In curtain fixtures, a shoe comprising a pin, a roll mounted on said pin and means engaging said pin and said roll for resisting the relative movement between them.

50 11. In curtain fixtures, shoes carried by a curtain, pins in said shoes, rotating guiding members in said shoes mounted upon said pins, and resiliently yieldable means engaging said pins and rotating guiding members for resisting the relative movement between them.

12. In curtain fixtures, a shoe comprising a pin, a rotating guiding member mounted on said pin, and resiliently yieldable means engaging said pin and said rotating guiding member to restrain the rotation of said guiding member.

60 13. In curtain fixtures, a shoe comprising a pin, a roll mounted on said pin and resiliently yieldable means engaging said pin and

said roll for resisting the relative movement between them.

14. In curtain fixtures, a shoe comprising a pin, a rotating guiding member mounted on said pin, and a spring pressed clutch member engaging said pin and said rotating guiding member to lock said guiding member against rotation in one direction. 70

15. In curtain fixtures, a shoe comprising a pin, a rotating guiding member mounted on said pin, and a spring-actuated clutch engaging said pin and said rotating guiding member to lock said member against rotation in one direction. 75

16. In curtain fixtures, a shoe comprising a pin, a rotating guiding member mounted on said pin and an intermittently acting clutch engaging said pin and said rotating guiding member to lock said member against rotation in one direction. 80

17. In curtain fixtures, a curtain, shoes carried by said curtain, said shoes comprising pins, rotating guiding members mounted on said pins and spring-actuated clutches engaging said pins and said rotating guiding members to lock said members against rotation in one direction. 85 90

18. In curtain fixtures, a spring-actuated curtain, shoes carried by said curtain, pins in said shoes, rotating guiding members in said shoes mounted upon said pins to engage said guideways, and intermittently acting clutches engaging said members and said pins to lock said members against rotation in one direction. 95 100

19. In curtain fixtures, a spring actuated curtain, shoes carried by said curtain, pins in said shoes, a rotating guiding member mounted in each of said shoes upon one of said pins, intermittently acting clutches engaging said members and said pins, and guiding members in said shoes separated from said rotating guiding members. 105

20. In curtain fixtures, a spring-actuated curtain, shoes carried by said curtain, guiding members in said shoes comprising rotating guiding members, pins upon which said rotating guiding members are mounted and intermittently acting clutches engaging said rotating guiding members and said pins to lock each of said rotating guiding members against rotation in one direction. 110 115

21. In curtain fixtures, a shoe to coöperate with a guideway, said shoe comprising a pin secured therein, a rotating guiding member mounted on said pin, an intermittently acting clutch engaging said member and said pin to lock said member against rotation in one direction and a guide-roll mounted in said shoe and separated from said rotating guiding member. 120 125

22. In curtain fixtures, a spring-actuated curtain, guideways adjacent said curtain, shoes carried by said curtain and pressed into coöperation with said guideways; each 130

- of said shoes comprising a pin secured thereto, a rotating guiding member mounted on said pin, an intermittently acting clutch engaging said rotating member and pin to lock 5 said member against rotation by contact with said guideway when said shoe is moved upward, and a guide roll engaging said guideway and mounted in said shoe above said rotating guiding member.
- 10 23. In curtain fixtures, a spring-actuated curtain, shoes carried by said curtain, pins in said shoes, a rotating guiding member mounted in each of said shoes upon one of said pins, intermittently acting clutching 15 means engaging said members and said pins to restrain the rotation of said members in one direction and guiding members in said shoes separated from said rotating guiding members.
- 20 24. In curtain fixtures, a spring-actuated curtain, shoes carried by said curtain, pins in said shoes, rotating guiding members in said shoes mounted upon said pins and automatic clutching means engaging said members and 25 said pins to restrain the rotation of said members in one direction.
- 25 25. In curtain fixtures, a shoe comprising a pin, a rotating guiding member mounted on said pin and spring-actuated clutching 30 means engaging said pin and said guiding
- member to restrain the rotation of said guiding member in one direction.
26. In curtain fixtures, a shoe comprising a pin, a rotating guiding member mounted on said pin, and automatic clutching means 35 engaging said pin and said rotating guiding member to restrain the rotation of said guiding member in one direction.
27. In curtain fixtures, a shoe comprising a pin, a rotating guiding member mounted on said pin and automatic means engaging said pin and said rotating guiding member to restrain the rotation of said guiding member.
28. In curtain fixtures, a shoe comprising a pivot member, a roll mounted on said pivot 40 member and means engaging said pivot member and said roll for resisting the relative movement between them.
29. In curtain fixtures, a spring actuated curtain, shoes carried by said curtain, pivot members in said shoes, rotating guiding members in said shoes mounted upon said pivot members, and automatic clutching means engaging said members and said pivot members to restrain the rotation of said 45 members in one direction.
